UNITED STATES PATENT OFFICE.

GEORGE E. SWAN, OF PROVIDENCE, RHODE ISLAND.

BRAIDING-MACHINE ATTACHMENT.

Application filed November 15, 1921. Serial No. 515,293.

To all whom it may concern:

Be it known that I, GEORGE E. SWAN, a citizen of the United States, and a resident of Providence, in the county of Providence and State of Rhode Island, have invented new and useful Improvements in Braiding-Machine Attachments, of which the following is a full, clear, and exact description.

This invention relates to braiding machine attachments.

The general object of this invention is the provision of means associated with the rubber strands of an elastic braiding machine for causing the operation of the means provided for connecting the braiding machine to the prime mover to release the former from the latter upon the breaking of the rubber strands.

This and other objects of the invention will be more clearly understood from the following detailed description and accompanying drawings.

Figure 1 is a front elevation of the braiding machine with the braiding machine attachment mounted in position;

Figure 2 is an end elevation of the braiding machine with the braiding machine attachment in position;

Figure 3 is a side elevation of the clutch interposed between the prime mover and the braiding machine;

Figure 4 is a top plan view of the upper portion of the braiding machine attachment;

Figure 5 is a side elevation of the braiding machine attachment with part of the lower portion of the stop motion cut away to show the triggers and weight arms;

Figure 6 is a top plan view of the U-shaped lever associated with the weight arms; and

Figure 7 is a vertical section through the upper portion of the stop motion attachment.

Referring to the above-mentioned drawings, a braiding machine, comprising a frame 10 on which is mounted a sinuous track 11, bobbin carriers 12 and bobbins 13, is shown. A drum 14 on which rubber strands 18 are wound is supported on the lower section of the frame 10. The rubber strands 18 pass upward through tubes 15 and over pulleys 16 supported by the upper section of the frame. Bobbins 13 carry the threads 17 which are woven about the rubber strands 18. A clutch is interposed between the braiding machine and the

prime mover. This clutch comprises a shaft 19 supported by the braiding machine frame 10 on which is mounted a gear 20 that may be fixed in any position on the shaft by means of a set screw 21. A bevel gear 22 is loosely mounted on the shaft and rides on the collar 23 fixed to the shaft 19. A collar 24 is slidably mounted on the shaft 19 and provided with fingers 25 which project through openings in the collar 23 and engaging in openings in the bevel gear 22 thus connecting it to the shaft. A lever 26 is provided for raising the collar 24 and has a latch 27 attached thereto for engaging with a link 28 to hold it in raised position. The bevel gear 22 meshes with a bevel gear 29 which is driven by the prime mover. The above-described machine is not part of the invention but is described so that the operation of the stop motion attachment may be more clearly set forth.

A casing 30 (see Figure 7) is pivotally mounted on the frame 10 by means of a threaded bolt 31 fixed to the casing, and a bushing 32 is clamped to the casing by means of a nut 33. Slidably mounted in the casing 30 is a bolt 34 having on one end a lug 35. Extending upward from the casing 30 are two lugs 36 between which a bell crank 37 is mounted on a pin 38. The lower arm of bell crank 37 is forked and each prong is provided with a slot 39 in which a pin 40 projecting through the bolt 34 slides, thus making connection between the bolt 34 and bell crank 37. Normally the bolt 34 does not project over the sinuous track 11 into the path of the carriers 12 but is of sufficient length so that it may be operated to extend into the path of the carrier which when it comes in contact with the bolt will swing it and the casing in a horizontal plane. A connecting link 41 is provided to connect the bolt lug 35 with the link 28 with which the slide 27 engages.

Mounted on the lower portion of the frame 10 (see Figure 5) is a plate 42 which carries two posts 43 and 44. Supported by these posts are three axles 45, 46 and 47. The axle 46 is not in alinement with the axles 45 and 47. A plurality of weight arms 48 are loosely mounted on the axle 46. The number of weight arms will depend on the number of rubber strands carried by the particular braiding machine. These weight arms are not evenly balanced about the axle 46 but the portion of each

100

105

110

arm on one side of the axle is considerably longer and heavier than the portion extending on the other. A number of triggers 49 are loosely mounted on the axle 45, one for each weight arm. The upper end of each trigger is provided with a hook 50 which engages with a rubber strand. The lower end is provided with a projection 51 which engages with the short end of the weight arm and serves to hold the weight arm in a nearly vertical position, as shown in Figure 2. A U-shaped lever 52 is loosely mounted on the axle 47 and is normally held in the raised position shown in Figure 2 by means 10 of a spring 53. The spring 53 is attached to an arm 54 carried by the post 43 by means of a bolt 55 and nut 56. This bolt and nut 55 and 56 are provided so that the normal position of the lever 52 may be adjusted. A 20 connecting rod 57 is interposed between the lever 52 and the bell crank 37.

The operation of the device is as follows:

The triggers 49 are engaged with the rubber strands 18, and the weight arms 48 are 25 raised to the nearly vertical position shown in Figure 2 and engaged by the triggers 49. The triggers serve to hold the weight arms in this position as long as they are engaged with the rubber strands 18. The lever 52 is 30 raised to the normal position shown in Figure 2 by the spring 53 thus raising the connecting rod 57 and bell crank 37. The raising of the upper end of the bell crank 37 draws the bolt 34 outward and it does not 35 project into the path of the carriers 12. The lever 26 is then raised, operating the clutch to connect the braiding machine to the prime mover, and the connecting member 28 is moved into engagement with the latch 27 40 thus swinging the bolt 34 and casing 30 in a horizontal plane into the position shown in Figure 4. The braiding machine is now operating and will continue to operate until the clutch is released, disconnecting the 45 braiding machine from the prime mover. This release of the clutch is accomplished when one of the rubber strands 18 breaks. Upon the breaking of a rubber strand one of the triggers 49 is released and allows a 50 weight arm to fall into contact with the lever 52. This forces the lever 52 downward and draws the connecting rod 57 and the upper arm of the bell crank 37 downward. The bolt 34 is forced inward by the operation 55 of the bell crank 37 and takes the position shown by the dotted lines in Figure 4. The bolt 34 in this position projects over the sinuous track 11 into the path of the carriers 12 which engage with it and swing 60 it in a horizontal plane. The connecting member 28 is also swung in a horizontal plane by the swinging of the bolt 34, and the latch 27 is released, dropping the lever 26 which causes the collar 24 to slide downward on the shaft 19. This operation re-

leases the bevel gear 22 which now turns loosely on the shaft 19. The machine may be set in operation again by the connecting of the rubber strand and engaging the released trigger 49 therewith and raising the 70 weight 48 to its nearly vertical position shown in Figure 2.

I would state in conclusion that while the illustrated example constitutes a practical embodiment of my invention, I do not limit 75 myself strictly to the exact details herein illustrated since manifestly the same can be considerably varied without departing from the spirit of the invention as defined in the appended claims.

Claims.

1. In combination with an elastic braiding machine for working on rubber strands including a clutch mechanism for connecting it to a prime mover, an elastic braiding attachment comprising a plurality of triggers associated with rubber strands, a plurality of weights separately mounted and adapted to be engaged by said triggers, and means interposed between the weights and clutch mechanism for releasing the latter upon the release of a weight by the breaking of a rubber strand releasing a trigger.

2. In combination with an elastic braiding machine for working on rubber strands 95 including carriers and clutch means for connecting it to a prime mover, a stop motion attachment including a slideable bolt mounted on the braiding machine frame and so located that it may be moved into engagement with said carriers, means operated by the breaking of a rubber strand to slide said bolt into engagement with the carriers, and means operated by the carriers through said bolt to release said clutch mechanism.

3. In combination with an elastic braiding machine for working on rubber strands including bobbin carriers, and means for connecting it to a prime mover, a stop motion attachment comprising a bolt slidably mounted in a casing pivotally mounted on the braiding machine frame, links connecting the bolt to the means for connecting the braiding machine to a prime mover, means associated with the rubber strands to operate said bolt to move it into engagement with the braiding machine bobbin carriers upon the breaking of a rubber strand, said carriers serving to rotate said bolt about the axis of the casing pivot to release the means for connecting the braiding machine to the prime mover.

4. In combination with an elastic braiding machine for working on rubber strands including carriers and clutch means for connecting the braiding machine to a prime mover, a stop motion attachment comprising a bolt slideable in a casing pivotally mounted on a braiding machine frame, a plurality of triggers and weights associated with the

130

rubber strands having means in conjunction therewith for operating said bolt to move it into engagement with the carriers upon the breaking of a rubber strand, and means connected with the bolt for operating said clutch to disconnect the braiding machine from the prime mover.

5. In combination with a braiding machine for working on rubber strands including carriers and a clutch for connecting the braiding machine to a prime mover, a stop motion attachment comprising a bolt slidably mounted in a casing pivotally mounted on the braiding machine frame, means connecting the bolt to the clutch interposed between the braiding machine and the prime mover, a plurality of weights rotatably mounted on an axle supported on the braiding machine frame, a plurality of triggers for engaging the rubber strands and holding the weights in a raised position, and means interposed between the weights and the slideable bolt for operating the latter upon the release of the former by the breaking of a rubber strand.

6. In combination with an elastic braiding machine, a stop motion attachment comprising a bolt slidably mounted in a casing pivotally mounted on the braiding machine frame, means connecting the bolt with a clutch interposed between the braiding machine and the prime mover, a plurality of weight arms loosely mounted on a shaft carried by the braiding machine frame, triggers for engaging the rubber strands associated with said weight arms for normally holding them in a raised position, a spring-controlled lever operated by any of the weight arms upon their release from the trigger by the breaking of a rubber strand, and a connecting rod and bell crank interposed between said lever and slideable bolt to operate the latter upon the operation of the former by the weight arms.

45 7. In combination with an elastic braiding machine, a stop motion attachment comprising a bolt slidably mounted in a casing pivotally mounted on the braiding machine frame, means connecting the bolt to a clutch

interposed between the braiding machine and prime mover, a plurality of weight arms loosely mounted in the shaft carried by the braiding machine frame, a plurality of triggers for engaging the rubber strands associated with the weight arms to hold them in a raised position, a spring - controlled U-shaped lever in conjunction with the weight arms and operated thereby, a bell crank carried by the bolt casing and associated with the bolt, and a connecting rod interposed between the U-shaped lever and bell crank to operate the bolt upon the breaking of a rubber strand to project the latter into the path of the braiding machine carriers, said carriers serving to swing the bolt in a horizontal plane to operate the clutch.

8. In combination with an elastic braiding machine, a stop motion attachment comprising a bolt slidably mounted in a casing pivotally mounted on the braiding machine frame, said bolt being so located that it may be moved into the path of the carriers, means connecting the bolt with a clutch interposed between the braiding machine and the prime mover, a plurality of weight arm loosely mounted on the shaft carried by the braiding machine frame, means controlled by the rubber strands for normally holding the weight arms in a raised position, and means operated by the weight arms upon their release by the breaking of a rubber strand to project the bolt into the path of the carriers, said carriers serving to swing the bolt in a horizontal plane to operate the clutch.

9. In combination with a braiding machine for working strands including a clutch mechanism for connecting it to a prime mover, a braiding machine attachment comprising means for releasing the clutch mechanism, weight members for operating the clutch releasing mechanism, and triggers separately mounted for normally holding the weight members out of engagement with the clutch releasing mechanism, said triggers being held in engagement with the weight members by the strands and released therefrom upon the breaking of the strands.

GEORGE EDWARD SWAN.
